[57] CLAIM

The ornamental design for a connector housing, as shown and described.

DESCRIPTION

FIG. 1 is a front elevational view of a connector housing showing our new design,

FIG. 2 is a rear elevational view thereof;

FIG. 3 is a top plan view thereof;

FIG. 4 is a bottom plan view thereof;

FIG. 5 is a right side elevational view thereof, the left side being a mirror image;

FIG. 6 is a cross-sectional view thereof taken along line VI—VI of FIG. 1.

FIG. 1

FIG. 2

FIG. 3

FIG. 4

FIG. 5

FIG. 6
